UNITED STATES PATENT OFFICE

PIERRE J. CHÉRON, OF STRATFORD, CONNECTICUT

DESIGN FOR AN ELECTRIC WALL PLUG

Application filed April 1, 1931. Serial No. 39,319. Term of patent 3½ years.

To all whom it may concern:

Be it known that I, PIERRE J. CHÉRON, a citizen of the United States, residing in Stratford, county of Fairfield and State of Connecticut, have invented a new, original, and ornamental Design for an Electric Wall Plug, of which the following is a specification, reference being had to the accompanying drawings, forming a part thereof.

Figure 1 is a side elevation of an electric wall plug showing my new design, and

Figure 2 is a plan view of the same.

I claim:

The ornamental design for an electric wall plug as shown.

PIERRE J. CHÉRON.
